US0D1048768S

(12) United States Design Patent (10) Patent No.: US D1,048,768 S
(45) Date of Patent:  Oct. 29, 2024

(54) LEG PILLOW

(71) Applicant: Rong Chen, Xiamen (CN)

(72) Inventor: Rong Chen, Xiamen (CN)

() Term: 15 Years

(21) Appl. No.: 35/519,853

(22) Filed: Jan. 10, 2024

(80) Hague Agreement Data

Int. Filing Date: Jan. 10, 2024

Int. Reg. No.: DM/234780

Int. Reg. Date: Jan. 10, 2024

Int. Reg. Pub. Date: Feb. 2, 2024

(51) LOC (14) Cl. 06-09

(52) U.S. Cl.

USPC D6/601

(58) Field of Classification Search

USPC D6/596, 597, 601, 604; D21/686; D24/183, 192
CPC A47G 9/10; A47G 9/1009; A47G 9/1045;
